WIG CONSTRUCTION

Emil A. Corsillo, Los Angeles, Calif.

Application September 6, 1950, Serial No. 183,417

3 Claims. (Cl. 132—54)

1

This invention relates to wigs and other types of artificial hair structures, and more particularly to improvements in the foundation frames upon which hair material is secured in the manufacture of wigs and the like.

More particularly, the reinforced wig foundation of the present invention is designed primarily for use in wigs of the type commonly used on clothing display mannequins, but it is to be understood that it is not necessarily limited to such use.

An object of my present invention is to provide novel and highly efficient reinforcement for the foundation member of a wig or the like, whereby is attained enhanced security against accidental dislodgement of the wig from the head upon which it is being worn, and against displacement of the wig from the exact position in which it has been adjusted upon the head.

A further object in this connection is to make it possible to seat a wig securely in the exact position desired upon a head, in spite of the fact that the wig might not be of the exact size which that particular head calls for. This feature of the present invention makes it particularly advantageous for use in wigs designed for display figures, particularly those used by the larger commercial establishments requiring a relatively large number of such fixtures to dress their windows and for display purposes elsewhere, as throughout a large store or show room. It is common practice in selecting a mannequin to display a particular garment, to give consideration to size, posture, and the like, to suit the garment and the surrounding environment in which the display is to be arranged, but without regard to the color, style, or arrangement of the hair, since after other considerations have been taken care of, a suitable wig can be fitted to the figure's head. It has been found, however, that the wigs of a certain head size carried in stock by a large department store, for example, are interchangeable among all the display figures having that certain head size. But there is no uniformity of head size in commercially available display figures; and consequently it is necessary for a firm of this nature to stock a large assortment of wigs in each of the many different head sizes apt to be found among the assortment of display figures on hand. Since the wigs used for display purposes must be of an exceptionally high quality in order to meet the exacting demands of display advertising, keeping such a large stock of display wigs in stock necessitates a very substantial item of ex-

2

pense. The present invention alleviates this condition to a very considerable degree, by making each wig applicable to display figures having more than a single head size, without detriment to the final appearance of the figure. In fact, the present invention increases the facility with which a wig can be mounted on the head of a display in the exact position desired by the dresser to create a particular effect.

A further object of my invention is to provide a reinforced wig foundation possessed of the advantages hereinabove mentioned, and which is of such a simple nature that its added cost is negligible and it can be incorporated into the structure of the wig foundation as an incidental step in the manufacture so simply and easily that it does not complicate the process of manufacture to any appreciable degree.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

30 Referring to the drawings:

Figure 1 is a perspective view of a head wearing a wig incorporating the principles of the present invention.

Figure 2 is a perspective view of the foundation member of the wig of Figure 1 prior to the attachment of the hair material thereto. A portion of one of the plies of the foundation member is turned back the better to reveal the details of the present invention.

40 Figure 3 is a transverse, vertical sectional view, the plane of section being indicated by the line 3—3 of Figure 1 and the direction of view by the arrows.

Figure 4 is a detail view in horizontal section, taken upon the line 4—4 of Figure 3, with the direction of view as indicated by the arrows.

In the commercial manufacture of wigs, whether they are to be worn by humans or to be used upon display figures, it is customary practice to employ a foundation member such as that indicated at 6 to the upper surface of which the hair material 7 is affixed. The hair material can optionally be human hair, horse hair, or, particularly when the wigs are to be used for display purposes rather than to be worn

on the human head, the hair material 7 frequently employed is rayon, nylon, hemp, or other stranded or fibrous material. The strands are affixed to the foundation member 6 in any suitable manner such as being stitched thereto or by being entwined with the cross strands of the material of which the foundation member 6 is constructed.

The foundation member 6 is conventionally made of a suitable number of layers or plies of a comparatively stiff textile fabric, such as buckram. These several plies are regularly bonded together into a unitary structure by starch which serves the added purpose of increasing the inherent stiffness of the completed foundation member 6. However, before the starch is permitted to dry it is shaped, as upon a suitable form, so as to be convex on its upper surface and concave on its under surface substantially to the form and size of the head which the wig being constructed is intended to fit. The foundation member 6 is so constructed that, when worn upon the head, it covers a major portion of the area of the top and the back of the head on which hair normally grows, or in the case of a wig being constructed for use upon a display figure, the corresponding portions of the head of such a figure. Each of the two sides 8 of the foundation member 6 is conventionally provided with a notch 9 in its lower edge of such size and so positioned that it is adapted to accommodate the ear 11 of the person or display figure wearing the wig; and a relatively narrow tongue 12 extends downwards from the lower edge of the foundation member 6 just forward of each of these notches 9. In the human head there is normally a slight depression in the skull just forward of the ears; and accordingly if these tongues 12 can be made to curve inwards slightly at and adjacent their lower ends they can be made to serve efficiently in securing the foundation member 6 in fixed position upon the human head or, in the event that the head of a display figure is similarly provided with a corresponding slight depression immediately in front of each of its ears, a wig can similarly be disposed with a substantial degree of security thereupon.

My invention contemplates the provision of reinforcing means for the foundation member 6 of wigs of the general character described which operate to impart to the wig the added degree of security with which it remains in position upon a head, by making the tongues 12 of the foundation member 6 materially stiffer than in wigs constructed in accordance with conventional practice and thereby making it possible to impart the inward curvature to the lower portions of the tongues 12 which will enable them to seat so firmly within the depressions just forward of the ears, to which reference has been made hereinabove, that the wig of which they are part will remain securely in the exact position to which it has been adjusted upon the head with a very substantial degree of dependability. I accomplish this purpose of the present invention by imbedding a small strip 16 of material within each side 8 of the foundation member 6, with the lower end of each of these strips 16 extending downwards throughout the entire length of the associated tongue 12, as clearly shown in Figure 2.

The principal requirements of the material of which these strips 16 are formed are that it shall be materially stiffer than the material of which the foundation member 6 is constructed.

and yet that it shall be possessed of an elastic limit considerably less than that of the material of the foundation 6. Being possessed of the first of these requirements, i. e., that it shall be stiffer than the material of the foundation, the presence of the reinforcing strip 16 in each of the tongues 12 will impart to that tongue a degree of stiffness considerably greater than that characterizing the tongue of a weak foundation not so reinforced and consequently much better able to retain any shape or configuration to which it is formed. The second essential characteristic of the material of each strip 16, to wit, its having a lesser elastic limit than the fabric of the foundation 6, permits bending the portion of the foundation within which the strips 16 are embedded far enough to exceed the elastic limits of the material of the strips 16 and then to release the pressure exerted against the material in so bending it without the tendency for the bent portion of the foundation 6 to return to its initial position. These two features of the strips 16 in co-operation with each other permit moulding or shaping the foundation 6 within which they are incorporated to the exact configuration and curvature which the requirements of any particular circumstances may dictate. Without being so reinforced, each of the tongues 12 could be deflected inwards considerably more easily, causing them to fit into the hereinabove mentioned hollows, or depressions, in the head being fitted, just forward of the ears, because of the fact that when not reinforced in the manner described the tongues are not as stiff. But being possessed of the relatively high coefficient of elasticity the tongues would be much more apt to spring back into their original position with the result that they would not have the ability of locking or anchoring the foundation 6 securely upon the head. On the other hand, when the reinforcing strips 16 are incorporated into the tongues 12 and the immediately adjacent portions of the foundation 6, the tongues 12 can, by exerting a somewhat greater degree of pressure thereagainst than is required when the tongues are not reinforced, be bent to any desired configuration, causing them to fit nicely within the described depressions. Then, because of the fact that the strips 16 have a relatively low elastic limit, the tongues will remain in the configuration to which they have been formed, with the result that they develop a key or lock where they fit within the depressions in the side of the head, thus causing the wig of which the foundation 6 is a part to remain securely in the exact position to which it has been adjusted upon the head.

Whereas there are undoubtedly a wide variety of materials possessed of the two described essential qualifications, the material which I prefer to use for each of the reinforcing strips 16 is the type of material known commercially as "hardware cloth." This material is of the nature of an open wire mesh, having openings substantially one-quarter inch square and composed of interwoven and respectively interconnected wires of soft iron or copper or other material having a relatively low elastic limit. Were strips of metal substituted for the hardware cloth, they undoubtedly would be possessed of sufficient stiffness and by employing suitable metal such, for example, as lead they would be possessed of a suitably low elastic limit, but, being in sheet form, it would be difficult or impossible to flex them about axes which intersect in the sheet. Consequently, it would be difficult or impossible to flex such

sheets to form a rounded concavity or cupped, or on the other hand, a domed portion. But by employing the hardware cloth for the present purpose, I have made it possible to shape the portions of the wig foundation 6 within which the strips 16 are embedded in any manner which any particular case may require.

For example, the lower end of the tongue 12 may be bent inward, and then without destroying this curvature about a substantially horizontal axis, the tongue may be flexed about a substantially vertical axis so that it is of arcuate form in horizontal section as well as in vertical section, this of course enables an operator to fit the inner surface of the tongue exactly to the curvature of the hollow or depression to which it is to be fitted.

Similarly with respect to the portion 21 of each side 8 of the foundation 6 immediately above the associated tongue 12. This portion of the foundation must have a curvature considered from front to back, i. e., arcuate about a vertical axis; and it also must have a curvature considered from top to bottom, i. e., arcuate about a horizontal axis. Were the strip 16 a solid sheet of metal, it would be impossible or difficult to develop this compound curvature about axes intersecting in the strip itself, but one of the peculiarities of hardware cloth is that it is subject to flexure about two or even more axes which intersect within the sheet of hardware cloth itself.

Consequently, the presence of the strips 16 of hardware cloth within the sides 8 and tongues 12 of the foundation 6 not only permits the tongues to be fitted and anchored with a substantial degree of security within the hollows or depressions in the sides of the head so as to secure the foundation firmly in position upon the head, but it also facilitates in shaping the domed portion of the foundation 6 itself. By their presence within the sides 8 of the foundation 6, the strips 16 of hardware cloth assist very materially in imparting the exact degree of forward and aft curvature and also the exact degree of up and down curvature that may be necessary to fit the wig nicely to the head by which it is to be worn.

So efficient have these strips 16 of hardware cloth embedded within the sides 8 and tongues 12 of the foundation 6 of a wig been proven to be when used commercially, that I have found it entirely feasible to employ a single size of wig to fit heads of various sizes. For example, a wig designed to fit a size 7 head can be used with perfect satisfaction upon heads ranging in size from 6½ to 7½ hat sizes; or a wig made for a size 21 head can be used with substantially equal satisfaction upon heads ranging in size from 19 to 22½. It is because of this feature of the present invention that a much lesser number of wigs need be kept in stock by an establishment using a relatively large number of display figures, as explained in greater detail in the objects hereinabove set forth.

An even further range of adaptability of the wig of my present invention to different head sizes is attained by forming the foundation with a pleat such as that shown in the back portion 65 of the foundation in Fig. 3 and revealed in hori-

zontal section in Fig. 4. Preferably before the starch with which the fabric of the foundation has been treated has been permitted to set, the material of the foundation is folded over and creased on itself in a pleat relatively wide at the lower edge of the foundation and tapering upward to a point which may advantageously be approximately half the distance between the lower edge and the top of the crown. After the starch has set, the pleat may be partly or completely opened, thus attaining an increase in the length of the periphery, or edge of the foundation. Nevertheless, the inherent stiffness of the heavily starched fabric maintains a tendency for the pleat to close and thereby impose a resilient tension on the foundation to seat firmly upon the head.

I claim:

1. In a wig construction, a foundation member comprising a plurality of sheets of textile fabric impregnated with starch to stiffen and adhesively unite said sheets into a unitary structure shaped substantially in conformity with top and back portions of the head on which hair normally grows, and a reinforcing strip of hardware cloth embedded within said foundation member between said sheets of fabric.
2. In a wig construction, a foundation member comprising a plurality of sheets of textile fabric impregnated with starch to stiffen and adhesively unite said sheets into a unitary structure shaped substantially in conformity with top and back portions of the head on which hair normally grows, and strips of hardware cloth embedded within those portions of said foundation adapted to overlie the portions of the head just forward of the ears.
3. In a wig construction, a foundation member comprising a plurality of sheets of textile fabric impregnated with starch to stiffen and adhesively unite said sheets into a unitary structure shaped substantially in conformity with top and back portions of the head on which hair normally grows, and reinforcing material affixed to those portions of said foundation adapted to overlie the portion of the head just forward of the ears, said reinforcing material being embedded within said foundation by being disposed between said textile fabric sheets, said reinforcing material being characterized by a substantially greater degree of stiffness than said starched fabric and by a relatively low elastic limit, whereby said portions of said foundations are adapted to be flexed less easily than other portions of said foundation but are caused to retain the form into which they are bent by such flexure.

EMIL A. CORSILLO.
